UNITED STATES PATENT OFFICE

2,381,331

TERMINAL CONNECTOR

Edgar H. Ayers, Schenectady, N. Y., assignor to
General Electric Company, a corporation of
New York

Application October 15, 1943, Serial No. 506,370

3 Claims. (Cl. 173—324)

My invention relates to terminal connectors, more particularly to terminal connectors of the detachable type such as used to join wires or cables to the terminals of an electric switch or contactor, and has for its object a simple and reliable connector for connecting a plurality of wires or cables to a terminal member.

In carrying out my invention in one form I provide a tubular member having an oblong cross section, which member is detachably mounted on the end of the terminal by means of a portion of reduced width on the terminal extending through the tubular member and terminating on each side of the tubular member in projecting shoulders, together with a clamping member extending through the tubular member and provided with shoulders for securing it in position. At the end of the tubular member adjacent the terminal I provide a screw for clamping the ends of wires or cables inserted between the terminal and clamping member and between the clamping member and the opposite end of the tubular member.

For a more complete understanding of my invention, reference should be had to the accompanying drawing, Fig. 1 of which is a side elevation view of a terminal connector embodying my invention as utilized to plant two cables through a contactor terminal; while Fig. 2 is an exploded view in perspective of the parts of the connector.

I have shown my invention in one form as applied to the electrically conducting terminal member 10 of an electric switch or contactor having a stationary contact 11 surrounded by a cup-like shield secured to it in electrically conducting relation. It will be understood that the terminal 10 is secured suitably to a support (not shown) on which also are mounted additional terminals and contacts, as well as movable contacts and operating means therefor.

In accordance with my invention, I form the end of the terminal 10 as a strip or strap and provide a portion 12 of reduced width with shoulder projections 13 and 14 at its outer and inner ends. The width of this portion 12 is slightly less than the inner width dimension of a rigid tubular member 15 having an oblong cross section. I also provide a separate clamping member 16 having a shape similar to the end of the terminal, it being provided with a central portion having a width somewhat less than the internal width of the member 15 and having projecting shoulders at each end. One end of the tubular member is provided with a tapped

hole 17 in which fits a clamping screw 18. As shown in Fig. 1 the pair of shoulders on each side of the terminal and the clamping member embrace the adjacent side of the member 15 thereby holding the member 15 on the terminal and holding the clamping member in the member 15.

For the purpose of securing one of the wires or cables more firmly, the lower end of the member 15 is shaped with a V cross-section and a plurality of projections 19 are provided on the inner surface of each side of the V-shaped portion. These projections are preferably made by striking indentations into the metal of the member from the exterior, as indicated in Fig. 1. Also, more firmly to secure the ends of the wires or cables, the clamping member 16 is formed with an inverted V-shaped cross section. Its upper surface, as seen in Figs. 1 and 2, and also its lower surface (not shown) is knurled or roughened by striking indentations in its surface. Likewise the portion 12 of the terminal is formed with an inverted V-shaped cross section.

As shown in Fig. 1, the elongated member 15 is mounted on the end of the terminal, it being slipped in place by first turning it approximately 90 degrees from the relative positions shown in Figs. 1 and 2, then slipping it over the shoulders 13 and turning to an upright position on the portion 12. The clamping member 16 is inserted in the tubular member by turning it through an angle of approximately 90 degrees before insertion in a similar manner. It will be observed that the portion 12 has its upper or convex side adjacent the upper end of the member while the clamping member 16 is arranged with its convex side adjacent the concave side of the portion 12.

As shown in Fig. 1, the ends of conductors, such as the wires or cables 20 and 21, are inserted respectively between the portion 12 and the clamping member 16, and between the clamping member 16 and the lower end of the tubular member 15. At this time the clamping screw 18 is turned upward, as viewed in Fig. 1, to provide for ease in the insertion of the ends of the wires. Then the screw 18 is turned downward tightly against the portion 12 of the terminal whereby the tubular member is pulled upward and the ends of the two wires clamped firmly in place. Thus the lower end of the tubular member with the projections 19 clamps the end of the wire 21 tightly against the lower or concave side of the member 16, while at the same time

the upper knurled convex side of the member 16 is forced tightly against the wire 20, thus securing the wire 20 between the member 16 and the concave side of the portion 12 of the terminal.

The various parts of my terminal connector, and also the terminal 10, are made of a suitable electrically conducting material such as brass or copper.

While I have shown a particular embodiment of my invention, it will be understood, of course, that I do not wish to be limited thereto since many modifications may be made, and I therefore contemplate by the appended claims to cover any such modifications as fall within the true spirit and scope of my invention.

What I claim as new and desire to secure by Letters Patent of the United States, is:

1. A connector comprising a terminal strap, a rigid flattened tubular member slidably mounted on said terminal strap, a clamping member slidably mounted in said tubular member, said terminal strap and said clamping member having V-shaped cross sections and said terminal strap being positioned in said tubular member with its convex side adjacent one end of said tubular member and said clamping member having its convex side adjacent the concave side of said terminal strap, and a clamping screw in the end of said tubular member adjacent said terminal strap for engaging said terminal strap whereby the ends of conductors inserted respectively between said terminal strap and said clamping member and between said clamping member and the other end of said tubular member are clamped by said screw in good electrically conducting relation with said terminal strap.

2. A connector comprising a terminal member provided with a portion of reduced width with shoulders at each end of said portion, a rigid flattened tubular member mounted on said portion and secured in place by said shoulders at each end of said portion, a clamping member

extending through said tubular member having projections at each end for securing it in said tubular member, said portion and said clamping member having V-shaped cross sections and said portion being positioned in said tubular member with its convex side adjacent one end of said tubular member and said clamping member having its convex side adjacent the concave side of said portion, and a clamping screw in the end of said tubular member adjacent said portion for engaging said portion whereby the ends of conductors inserted respectively between said portion and said clamping member and between said clamping member and the other end of said tubular member are clamped by said screw in good electrically conducting relation with the end of said terminal.

3. A connector comprising a terminal provided with a portion of reduced width with shoulders at each end of said portion, a rigid flattened tubular member mounted on said portion and secured in place by said shoulders at each end of said portion, a clamping member extending through said tubular member having projections at each end for securing it in said tubular member, said portion and said clamping member having inverted V shapes and said clamping member being provided with a roughened upper convex surface, a clamping screw in one end of said tubular member for engaging said portion, the lower end of said tubular member being V-shaped and projections on the inner sides of said lower portion whereby the ends of conductors inserted respectively between the concave side of said portion and the roughened convex side of said clamping member and between the convex side of said clamping member and said other end of said tubular member are clamped by means of said screw in good electrically conducting relation with said reduced portion of said terminal.
